UNITED STATES PATENT OFFICE.

EMANUEL FRIENDLICH, OF KANSAS CITY, MISSOURI.

SHOW-FIXTURE.

SPECIFICATION forming part of Letters Patent No. 488,757, dated December 27, 1892.

Application filed April 26, 1892. Serial No. 430,671. (No model.)

To all whom it may concern:

Be it known that I, EMANUEL FRIENDLICH, of Kansas City, Jackson county, Missouri, have invented certain new and useful Im- 5 provements in Show-Fixtures, of which the following is a full, clear, and exact description, reference being had to the accompanying drawings, forming a part hereof.

My invention relates to appliances for dis- 10 playing merchandise in the windows and other parts of stores, and the objects of my invention are to produce a show-fixture which shall be simple, strong, durable, and inexpensive in construction, and capable of being readily put together and taken apart, and which shall also possess great capacity for holding the merchandise or goods, and which, furthermore, shall be adapted for effective location in a great variety of situations.

20 To the above purposes my invention consists in certain peculiar and novel features of construction and arrangement, as hereinafter described and claimed.

In order that my invention may be fully understood, I will proceed to describe it with reference to the accompanying drawings, in which;

Figure 1 is a front elevation, partly in vertical cross-section, of a show-fixture embodying my invention. Fig. 2 is an end elevation of the same. Fig. 3 is a view similar to Fig. 1, but showing certain modified features of construction. Fig. 4 is an end elevation of the same. Fig. 5 is a detached perspective 30 view of one of the devices for connecting the ends of the supporting-chains. Fig. 6 is a detached perspective view of one of the skeleton-links shown in Figs. 1 and 2. Fig. 7 is a detached perspective view of a modified form 35 of the attaching-device shown in Fig. 5. Fig. 8 is a detached plan view of a modified form of supporting-link. Fig. 9 is a detached perspective view of a further modification of the attaching devices for the supporting-chains. Fig. 10 is a detached perspective view of a 40 still further modification of the attaching device. Fig. 11 shows a peculiar form of screw, used in attaching the nuts to a suitable support.

45 In Figs. 1, 2, 3, and 4, let 1 designate the bottom and 2 the top of the show-window; these parts being so indicated simply for pur-

poses of illustration, and it being understood that the part 1 may be a counter or shelf, or other suitable support, while the part 2 may 55 be a ceiling, or any structure located above the part 1. Into the part 2 is driven vertically a screw 3, the outer portion of which, adjacent to the head, is formed angular, as shown at 4, for the purpose of receiving a 60 wrench or spanner for turning the screw so as to force the same into the part 2 or so as to wholly or partially withdraw the same from said part, as desired.

Between the outer terminus of the angular 65 portion 4 of the screw 3 and the head of said screw is interposed a plain cylindrical portion, 5, for a purpose to be hereinafter explained, and from the opposite end of this angular portion 4 extends the externally screw- 70 threaded stem 6 of the screw. As shown, two of these screws 3 are driven into the part 2 so as to depend downward therefrom, and two other and precisely similar screws 3 are driven into the part 1, so as to project vertically upward therefrom. The outer end of 75 each of these screws is embraced by a nut 7, which is shown as of quadrangular form, but which may be of octagonal, or any other polygonal form, as desired. Each of these nuts 80 is formed with a central vertical bore 8 one end of which is formed with an enlarged countersink 9 to receive the head of the screw 3.

In Figs. 1, 2, and 5, 10 designates a U- 85 shaped bail which is formed preferably of stout wire, and the ends of which embrace opposite sides of the nut 7; the extremities of the arms loosely surrounding two screws 11 which are inserted into opposite sides of the 90 nut 7. It is to be observed that each of the two lower nuts 7 are located perpendicularly below each of the upper nuts 7 and that the bail 10 of the lower nuts are inverted, while the bail 10 of the upper nuts are reverted. 95

Between each pair of nuts 7 is interposed a vertical flexible support 12, there being thus two of said supports to each fixture, and into these supports are inserted (in a manner hereinafter fully explained) the ends of any desired number of horizontal supports 13; said supports being in the form of rods or bars, either of wood or metal, and being of any suitable or preferred length. 100

In Figs. 1 and 2, the said vertical flexible supports 12 are shown as composed of a number of skeleton links 14, one of which is shown detached in Fig. 6. Each of these links 14 is formed of a single piece of stout wire which is so bent as to form two vertical parallel arms 15 the upper ends of which terminate in hooks 16. The lower ends of these two arms 15 are bent upwardly, as at 17, so as to form two inner parallel vertical arms 18. The upper ends of the arms 18 are bent upon themselves one or more times to form an opening or eye 19, into which one end of the corresponding supporting rod or bar 13 is inserted.

In setting up the fixture, after the nuts 7 and their bail 10 are placed in position, a V-shaped connecting-piece 20 is first attached to each bail 10; the bend of said connecting-piece embracing the horizontal arm of the bail, and a transverse pin 21 extending through the outer ends of the connecting-piece. A second connecting-piece 22, having turned ends 23, is connected to the corresponding pin 21, by bending one of its bends 23 around the pin, and the opposite bend 23 of said second connecting-piece 22 is then caused to surround either the upper or lower horizontal arm of the loop 19 of the corresponding link 14, according as said link is at the upper or lower end of the flexible support 12. The hooks 16 of one link are engaged with the bends 17 of the succeeding link, until the desired length has been given to the flexible support 12.

It will be seen that in setting up the fixture above described, the screws 3 are free to be turned in the nuts 7, either by a suitable wrench or spanner applied to the angular portions 4 of the screws, or by a screw-driver applied to the nicks in the heads of the screws, and that after the screws have been properly inserted, the fixture is retained strongly in its required position, so as to properly support the goods to be displayed; such goods being placed upon the bars or rods 13.

In Fig. 7 I have shown a slightly modified form of the bail for the nut 7; the bail 24 being, in this instance also of stout wire, and having a skeleton hook 25 formed in its middle. The hooks 25 engage the upper or lower arms of the loops 19, according as the bails are at the upper or lower ends of the flexible supports 12.

In Figs. 3, 4, and 8, I have shown a modified form of the links which compose the flexible supports. Each link 26, is, in this instance, formed of a strip of suitable flexible sheet-metal; the body-portion of the blank from which the link is formed being thus of elongated rectangular form, as shown in Fig. 8. At each end of the body-portion of the blank is formed a reduced portion or neck 27 at the outer end of which is formed a transverse skeleton enlargement or head 28. An opening or eye 29 is formed through each end of the body-portion of the blank, as shown, and when the link is completed its blank is dou-

bled upon itself, at the point indicated by the dotted line in Fig. 8, so as to receive the end of the corresponding supporting bar or rod 13. In this instance, no second connecting-piece 22 is necessary; the bend of each link passing through the skeleton heads 28 of the succeeding link, and the bends of the upper and lower links embracing the pins 21 of the upper and lower V-shaped connecting-pieces 20.

In Fig. 9 I have shown a further modification of the construction of the attaching devices which are carried by the nut 7. In this instance two arms 30 are employed, instead of the bails 10 and 24, said arms being of straight form and each at one end loosely embracing the screw 11, and also at their opposite ends similarly embracing the ends of a pair of studs 31 which project from opposite sides of a disk 32. At opposite points of the disk 32, and intermediately of the studs 31 project outwardly two studs 33 which are embraced loosely by two ears 34 which are formed at opposite ends of the lower margin of a connecting-piece 35. The upper margin of this connecting-piece 35 is formed with a hooked bend 36, which is designed to engage the corresponding pin 21. It will thus be seen that universal movement is permitted to the connecting-piece 35, so as to enable said connecting-piece to adapt itself to the requirements of a great variety of situations.

In Fig. 10 I have shown a still further modification of the attachments carried by the nuts 7; whereby the device is adapted to be placed in corners and other similarly secluded places. In this instance, two arms 37 are secured, by two screws 11, to each side of the nut, and the upper ends of these arms unite integrally with a rectangular frame-piece 38. Four connecting-pieces 39 are connected to the four arms of the frame 38, by hooked lower margins 40 which loosely embrace the arms of said frame-piece. The upper ends of these connecting-pieces 39 are formed with similar hooked portions 40 which are designed to engage the pins 21 of the connecting-pieces 20.

From the above description, it will be seen that I have produced a show-fixture which is simple, strong, durable, and inexpensive in construction, capable of being placed in a great variety of situations, and of properly displaying a great variety of goods, and which can be readily set up and taken down, as desired.

Having thus described my invention, what I claim as new therein and desire to secure by Letters Patent, is:

1. A show-fixture comprising a number of flexible supports composed each of a number of interlocking links, nuts carrying pivotally attached connecting-pieces and connected to the extremities of the flexible supports, and attaching-screws passing through the nuts and into the upper and lower parts of an adjacent structure, substantially as set forth.

2. A show-fixture, comprising a number of flexible supports composed of a number of in-

terlocking links having openings or eyes, supporting bars or rods entering the eyes, nuts carrying pivotally attached connecting-pieces and connected to the extremities of the flexible supports, and attaching-screws passing through the nuts and into the upper and lower parts of an adjacent structure, substantially as set forth.

3. A show fixture, comprising a number of flexible supports, or linked chains, a number of the links having openings or eyes located oppositely to each other, bars or shelves sup-

ported at their ends in said oppositely disposed eyes, with swiveled nuts or fastenings located at each end of each chain through the medium of pivotal ball connections, substantially as described.

In testimony whereof I affix my signature in the presence of two witnesses.

EMANUEL FRIENDLICH.
